Primary Examiner — Charles D Hanson*(74) Attorney, Agent, or Firm* — Patterson Thuente
Pedersen, P.A.(57) **CLAIM**

We claim the ornamental design for a tibial implantable neurostimulator, as shown and described.

DESCRIPTION

FIG. 1 is a front perspective view of a tibial implantable neurostimulator.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a rear perspective view thereof.

Items shown in broken lines depict environment and portions of the tibial implantable neurostimulator that form no part of the claimed invention.
